UNITED STATES PATENT OFFICE.

PETER A. SCHWAB, OF NEW YORK, N. Y., ASSIGNOR TO ADAMS-WILLIAMS MANUFACTURING CORPORATION, OF NEW YORK, N. Y., A CORPORATION OF NEW YORK.

AUTOMOBILE-BODY CONSTRUCTION.

1,323,791.

Specification of Letters Patent. Patented Dec. 2, 1919.

Application filed July 17, 1917. Serial No. 180,989.

To all whom it may concern:

Be it known that I, PETER A. SCHWAB, a citizen of the United States, and resident of New York city, in the county of New York and State of New York, have invented certain new and useful Improvements in Automobile-Body Constructions, of which the following is a specification.

This invention is an improvement in automobile body construction and relates to the means for detachably securing in place the transparent panels used in converting the body into either an open touring car or a closed limousine. The invention is particularly adapted to that type shown in the Williams Patents Nos. 1,151,314 and 1,151,315, of August 24th, 1915, in which the panels have rigid frames with depending lugs for insertion in sockets in the upper edges of the hinged or stationary wall sections of the body.

My present invention has for its main object to provide a rigid, inexpensive and attractive construction particularly adapted to be embodied in a wall section of the car at the time the body is manufactured or inserted in the wall of a finished car already in use, to receive and hold the lug of the removable panel. I so design this support that it has no projecting parts and does not necessitate any alteration in the contour, shape or size of the wall section. The details of merely certain embodiments of my invention will be explained in connection with the accompanying drawings, in which

Figure 1 is a side elevation of a body construction in connection with which my improved construction may be employed;

Fig. 2 is a perspective view of a portion of the wall section, the outer casing being broken away;

Fig. 3 is a horizontal section approximately on the line 3—3 of Fig. 4;

Fig. 4 is a vertical section approximately on the line 4—4 of Fig. 3;

Fig. 5 is a perspective view of another form, adapted to be inserted in a mortised recess in the wall;

Fig. 6 is a perspective view of a third form; and

Fig. 7 is a vertical section through a wall embodying the form shown in Fig. 6.

In Fig. 1, I have shown a portion of an automobile having the usual body including stationary wall sections 10 and 11, and inter-

mediate hinged wall sections or doors 12 and 13. The body, at its rear, supports the framework of a type of top commonly known as a "one-man" top 14 and which has a horizontal bow extending substantially parallel to the upper edge of the body proper and secured to the upper edge of the wind shield stanchions 15. Intermediate these stanchions and an upwardly extending bow 16 of the top, there are provided four panels 17, 18, 19 and 20, corresponding to the four body sections 10, 11, 12 and 13 and each rigidly secured to its corresponding wall section.

These panels include rigid frames carrying transparent plates of glass, celluloid or other substance suitable for the purpose. The upper edges of the panels 17 and 18 which are carried by the stationary parts of the body may be secured to the horizontal bow of the top in any suitable manner if desired, while the panels 19 and 20 being carried by the hinged wall sections or doors 12 and 13 may be resiliently held in respect to the top bow by suitable means, as for instance, that shown in my companion application Serial No. 184,513, filed August 4th, 1917.

The wall sections 10, 11, 12 and 13, may vary in number and width, depending upon the type of car. In bodies with only a single door, there may be three panels, one carried by the door and one carried by the stationary wall section in advance of and one in the rear of said door. In other body constructions, no panel in front of the door need be employed and thus there would be only two panels on each side, one carried by the door and the other carried by the stationary wall in the rear of the door.

The features of construction so far referred to in detail form no portion of my invention and are illustrated and described merely to facilitate a clear understanding of a preferred use of my invention.

The wall sections, whether stationary or hinged are ordinarily formed of a wooden frame 21 with an outer sheet metal covering 22 which is ordinarily folded or rounded over the frame at the upper edge of the latter to give the wall section a smooth and attractive finished appearance and to conceal and protect the frame. In my present construction I cut away a portion of this wooden frame and embed therein the parts

going to make up the lug clamp. In the form shown in Figs. 2, 3 and 4, portions at opposite sides at the two upper corners are cut away to form recesses in which metal strips 23 and 24 constituting reinforcing members may be inserted. These may be of short metal bars of any desired cross section but are preferably rounded at their upper edges to facilitate the folding over of the outer casing 22 and they are preferably flat at their inner surfaces so as to fit firmly and snugly against the inner surfaces of the recesses.

Extending down into the top of the frame 15 is a lug receiving socket 25 of any desired depth and so positioned that the outer reinforcing strip or member 24 constitutes an outer wall for the socket.

Extending inwardly from the opposite 20 side of the frame is a recess 26 communicating with the socket 25 by a passage 27. Embedded within the recess 26 is a non-rotatable member 28 preferably in the form of a nut having a non-circular periphery and forced into the wood of the recess so as to be 25 firmly held against rotation. Between this nut and the side reinforcing member 23 is a collar or tube 29 serving as a spacing member and permanently holding the nut 28 at 30 a predetermined distance from the member 23. The member 23 has an aperture 30 therein communicating with the recess 26 and a clamping member 31 extends through 35 the nut 28 and the passage 27 and terminates in the socket 25. The opposite end of the clamping member 31, which is preferably a screw bolt may project out through the aperture 30 and be of such form that it may be readily grasped in the hand or it may 40 terminate within the recess 26. Preferably, the latter form is employed and the head is of such non-circular cross section that a key 45 may be inserted through the aperture 30 into the recess 26 and engage with and rotate the clamping member. The members 23 and 24 may be rigidly connected to the frame 21 in any suitable manner so as to be held 50 against outward movement, but preferably this securing means is in the form of a pair of screw bolts 32 extending through one strip and through the frame and having threaded 55 engagement in the other strip. Thus, when the clamping member 31 is rotated into firm engagement with the lug of the panel, the latter will be firmly clamped against the strip 24 and the latter will be held against any relative movement in respect to the nut 28 with which the clamping member has 60 threaded engagement.

65 All of these parts are extremely simple in their construction, easy to manufacture and require very little machining or other operations on them. The parts are preferably concealed by the outer casing 22 which is folded over the top of the frame as shown

particularly in Fig. 4. A suitable aperture is provided to register with the socket 25 and a second aperture to register with the recess 26.

I have shown the strips 23 and 24 comparatively short and disposed only at the upper corners of the frame. It will, of course, be evident that these strips may be as much longer as desired and in fact may extend along the entire upper edge from one 75 corner to the other so that the strips of the clamping device at one corner will be integral with those of the clamping device at the other corner. In fact, instead of cutting away portions of the frame to receive 80 these strips and other parts, the parts 23, 24, 28, 29, 31 and 32 in the relationship shown may be connected to a wooden strip separate from the main frame of the door and the latter may be secured directly to the 85 upper edge of the wall section. This provides a construction which may be readily applied to the completed wall sections of cars already in use. I have referred to only two of these clamping members, one at each 90 corner for engaging with two lugs on the wall panel. It will of course, be evident that a larger number of clamping devices may be provided and that they may be disposed in such position and in such number 95 as will correspond to the position and number of the depending lugs on the removable panels.

In Fig. 5 I have shown a modified form 100 in which the opposite walls of the lug receiving socket are integral and only one reinforcing or side strip is employed. In this construction, I employ a single casting including a facing or side reinforcing strip 24^a, a non-rotatable part 28^a and side connecting 105 parts 32^a. These three parts being integral are rigid in respect to each other and the parts 24^a and 28^a correspond to the parts 24 and 28 of Fig. 3 while the parts 32^a correspond to the means employed in the form 110 shown in Fig. 3, for preventing the separation of the parts 24 and 28. The lug receiving socket 25 is between the parts 24^a and 28^a and the clamping screw 31 is threaded through 115 the non-rotatable part 28^a. This device may be inserted within a mortised recess within the wall section of the automobile body in approximately the same position as is the device shown in Figs. 2, 3 and 4. The end of the clamping screw 31 preferably terminates within the wall and access may be gained to it through a hole bored in from the opposite surface of the wall and slightly larger than and in alignment with the clamping screw. The side or reinforcing strip 24^a 120 may be rigidly secured to the body of the wall section in any suitable manner. As shown, it has projecting end portions apertured to receive heavy wood screws or clamping bolts.

A further form is shown in Figs. 6 and 7 which is particularly adapted for use where it may be desired to vary the position of the lug receiving socket in respect to either surface of the wall section. This form includes a face plate 23^b corresponding to the part 23 of Fig. 3 and a non-rotatable part 28^b corresponding to the non-rotatable part 28 of Fig. 3. These two may be cast integral and be connected by side members 32^b corresponding to the means which holds the parts 23 and 28 of Fig. 3 rigid in respect to each other. Rigidly and adjustably connected to the casing is a U-shaped member 24^b spaced from the non-rotatable member 28^b to leave a lug receiving socket or aperture 25^b. The clamping member 31 is threaded through the member 28^b and when in operative position may clamp the lug of the panel against the member 24^b. The head of the clamping member preferably terminates within the recess between the members 23^b and 28^b and access may be gained to it by a key receiving opening 30^b in the part 23^b. Any suitable means may be employed for clamping the parts 24^b and 28^b rigid in respect to each other and permitting of an adjustment of the part 24^b in respect to the part 23^b. As shown, the part 24^b has side members 35 engaging with the outer surfaces of the parts 32^b and slotted to receive lugs 36 on the latter acting as guides to control the direction of relative movement of the parts in respect to each other. For holding them in adjusted position there are employed screws or rivets 37 extending through the slots in the members 35 and into the bridge made up of the parts 28^b and 32^b. For holding the device in position and rigid in respect to the frame or body of the wall section of the car, the side strip 23^b has apertures through its projecting ends to receive wood screws or clamping bolts. The side strip 23^b may be unfinished and embedded within a mortised opening in the frame as shown in Figs. 2, 3 and 4 in which event it need not be finished with any particular care or it may be made comparatively thin as shown and may be not only longer but also wider than the parts carried by it so that the device may be applied to the wall section of a car previously completed. It is merely necessary to cut a recess into the side of the wall adjacent to the top as shown in Fig. 7 and this recess may extend through the outer sheet metal covering 22 as well as into the wood. The thin marginal portions of the part 23^b will overlap the edges of the opening and form a cover plate for the recess as well as an anchorage for the parts acting to clamp the panel lug.

Having thus described my invention, what I claim as new and desire to secure by Letters Patent, is:

65 1. A convertible automobile body includ-

ing a wall section, a removable panel having a rigid frame and a depending lug, a pair of reinforcing members upon opposite sides of said wall section, a non-rotatable member between said reinforcing members and 70 a clamping member extending through said non-rotatable member for clamping said lug against one of said reinforcing members.

2. A convertible automobile body including a wall section, a removable panel having 75 a rigid frame and a depending lug, a pair of reinforcing members upon opposite sides of said wall section, a non-rotatable member between said reinforcing members and a clamping member extending through said 80 non-rotatable member for clamping said lug against one of said reinforcing members and means for spacing said non-rotatable member from the other of said reinforcing members.

3. A convertible automobile body including a wall section having a lug receiving socket in the upper edge thereof, reinforcing members upon opposite sides of said section, one of said members forming a side 90 wall for said socket, a screw threaded clamping member extending into said socket, and a casing covering the upper edge of said section and said members and having an aperture registering with said socket.

4. In combination, a wall section having a lug receiving socket in the upper edge thereof and a passage extending laterally from one side into said socket, reinforcing members upon opposite sides of said section, a non-rotatable member intermediate of said members, an annular member spacing said non-rotatable member from one of said reinforcing members and a clamping member having one end extending into said 100 socket and having the opposite end within said annular member.

5. In combination, a wall section, reinforcing members upon opposite sides thereof, a nut intermediate of said members, a collar spacing said nut from one of said members and a clamping screw extending through said nut toward the other of said members and having its head disposed within said collar.

6. In combination, a wall section, a pair of members embedded in the upper edge thereof and spaced apart to form a lug receiving opening therebetween, a clamping screw extending through one of said members into said socket and having its opposite end or head terminating within said wall section.

7. In combination, a wall section, a pair of members embedded in the upper edge 125 thereof and spaced apart to form a lug receiving opening therebetween, a clamping screw extending through one of said members into said socket and having its opposite end or head terminating within said 130

wall section, one of said members being materially longer than the other and having its end portion provided with apertures and means extending through said apertures for holding said members rigid in respect to said wall section.

8. In combination, a wall section having a wooden frame and a sheet metal covering, a lug clamp embedded within said frame 10 and having a lug receiving socket and a lug clamping screw, said sheet metal covering having an aperture registering with said socket and having a second aperture through which access may be gained to said clamp 15 ing screw.

9. In combination, a wall section, a strip extending along one edge thereof and rigidly secured thereto, a U-shaped bridge rigid with said strip embedded within said wall 20 section and having a portion spaced from said strip to leave a lug receiving socket and a clamping screw extending through one wall of said socket.

10. A convertible automobile body including a wall section having a wooden frame presenting a lug receiving opening 25 in the upper edge thereof, a reinforcing

strip embedded within said frame at one side of said opening, a member embedded within said frame at the opposite side of said opening and having a threaded passage therethrough, a clamping member extending through said passage into said opening, and a removable panel having a depending lug adapted to be rigidly clamped within said 30 opening by said clamping member.

11. A convertible automobile body including a wall section having a wooden frame presenting a lug receiving socket in the upper edge thereof, a member 40 embedded within said frame alongside said socket and having a threaded passage therethrough intersecting said socket, a clamping member within said passage, a sheet metal covering for said frame having 45 apertures registering with said socket and said passage, and a removable panel having a depending lug adapted to be clamped within said socket by said clamping member.

Signed at New York city in the county of New York, and State of New York this 9th day of July, A. D. 1917.

PETER A. SCHWAB.
